G. G. WILLIAMS,
BLOW-OUT BOOT,
FILED SEPT. 23, 1921.

1,445,465.

UNITED STATES PATENT OFFICE.

GEORGE G. WILLIAMS, OF DALLAS, TEXAS, ASSIGNEE TO FOWLER-WILLIAMS COMPANY, OF DALLAS, TEXAS.

BLOW-OUT BOOT.

Application filed September 23, 1921. Serial No. 502,642.

To all whom it may concern:

Be it known that I, GEORGE G. WILLIAMS, a citizen of the United States, residing at Dallas, in the county of Dallas and State of Texas, have invented certain new and useful Improvements in Blow-Out Boots, of which the following is a specification.

My invention relates to blow-out boots, and has particular reference to the provision 10 of a flap or covering for protecting the various forms of fastening means employed to hold the longitudinal edges of the boot in fixed relation.

In various forms of blow-out boots appearing on the market, the fastening means employed comprises flexible strips secured to opposite sides of the split edges of the boot and provided with interlocking portions or other fastening means for fastening 15 the edges of the boot in fixed relation about the inner tube beneath the "rim-cut" or "blow-out" in the outer casing. Many of these flexible strips are secured to the edges of the boot by rows of stitching or the like 20 which permanently connect the strips to the boot. In use, the constant friction or rubbing of the boot within the casing soon chafes or destroys the stitching and allows the boot to separate and blow out through 25 the hole in the outer casing beneath which the boot was disposed. Also rust from the metallic rims, sand, water, or other foreign substances enter the casing and tend to destroy or materially weaken the fabric 30 strips and stitching and to thus allow the boot to bulge or separate.

Further, many of the present boots are provided with tongue members secured to one edge of the boot and bordering upon 35 the opening and designed, when the two edges of the boot are joined, to lie between the inner tube and locking means to prevent the entry of dirt or other foreign substance between the inner surface of the boot and the inner tube and to prevent pinching of 40 the tube at the seam or joint. In use, it is found that notwithstanding this tongue member, particles of dirt or other foreign substance work into the interior of the boot 45 and in a comparatively short time wear a hole in the inner tube.

The object of this invention is to overcome the above disadvantages by providing a blow-out boot having a protective flap or 50 covering secured to the boot near the open-

ing, which when the boot is in fixed position about the inner tube, is capable of use for completely covering the fastening means which maintain the boot in fixed position.

A further object of this invention is to 60 provide a protective flap for covering the fastening means and also for protecting the stitching or the like, which secures the fastening strips to the boot.

A further object of this invention is to 65 provide a device of the above mentioned character which completely covers and protects the fastening means and prevents the entry of dirt or other foreign substances into the interior of the boot.

A still further object of this invention is to provide a device of this general character that is simple in construction, inexpensive to manufacture, convenient in use and strong and durable.

In the accompanying drawings, forming a part of this specification and in which like numerals are employed to designate like parts throughout the several views;

Fig. 1 is a perspective view of a blow-out boot of any well known or preferred construction showing my protective flap overlying the fastening means,

Fig. 2 is a plan view of one form of blow-out boot provided with my improved protective flap, showing the relative position of the flap with respect to its associated parts, and

Fig. 3 is a cross sectional view of a tire casing and inner tube showing the position 90 of the boot in actual use.

Referring to the drawings, wherein for the purpose of illustration is shown a preferred example of my invention, the numeral 6 designates a blow-out boot composed of 95 a plurality of laminations of fabric or the like, such as is the common construction of these boots. Attached to the opposite edges of the boot are the locking strips 7 and 8, secured to the boot by the line or lines of 100 stitching 9 and 10 respectively, and comprising, in the present instance, interlocking engageable tongue and slot members 11 and 12, for securely fastening the boot in fixed position about the inner tube 13 when the 105 blow-out boot is in use within a casing 14. A strip 15 is attached to one edge of the boot at the inside thereof, and is adapted, when the two edges of the boot are joined, to lie between the inner tube and seam or joint, 110

so that there is no danger of the inner tube becoming pinched at this point. The presence of this strip 15 also serves with a certain degree of utility to prevent the entry of dirt and other foreign substances into the boot.

The numeral 16 designates my improved protective flap or covering which forms the salient feature of the present invention. 10 This protective flap 16 is preferably made of tough and pliable rubber, leather, or textile fabric and has one of its edges secured to the boot in proximity to the fastening means employed to maintain the boot 15 in closed position. Experience has shown that a preferred method of securing this protective flap to the boot is to place one edge of the same beneath either of the flexible fastening strips during the manufacture 20 of the boot, and to utilize the same fastening means to secure both protective flap and fastening strip to the body of the boot. This method serves to reduce operations and secures the protective flap 16 in the proper 25 location with respect to the fastening means.

When it is desired to utilize the blow-out boot to protect an inner tube beneath a "rim-cut" or "blow-out" in the outer casing, the boot is placed around the partially inflated tube and the interlocking fastening 30 means engaged to secure the boot in the desired position. The protective flap 16 is then folded over to cover the fastening means, as shown in Fig. 1, and thus serves 35 to completely protect the stitching which secures the fastening strips to the boot and the particular form of fastening means employed. This protective flap when in this 40 position also covers the seam or joint between the two edges of the boot and assists in preventing the entry of dirt or other foreign substances into the interior of the boot where its presence would be highly objectionable.

It is to be understood that the form of 45 my invention shown and described herein is to be taken as a preferred example of the same, and that various changes in construction, size and arrangement of parts may be resorted to without departing from the 50 spirit of the invention or the scope of the subjoined claims.

Having thus described my invention what I claim as new and desire to secure by Letters Patent is:—

1. A blow-out boot, comprising a body portion, strips secured to opposite sides thereof, fastening means carried by said strips, and means for protecting said strips and fastening means when the boot is in 60 position about an inner tube.

2. A blow-out boot, comprising a body portion, strips secured to opposite sides thereof, fastening means carried by said strips, and a protective flap secured to the boot in proximity to the strips and fastening means and adapted to overlie said strips and fastening means when the boot is in 65 position about an inner tube.

3. A blow-out boot, comprising a body 70 portion, fastening means secured to the body portion at opposite sides thereof, and a protective flap having an edge secured to the body portion beneath one of said fastening means and adapted to overlie both fastening means when the boot is in position 75 about an inner tube.

4. A blow-out boot comprising a body portion, a pair of strips secured to opposite sides thereof, fastening means carried by said strips, and a protective flap having an edge secured to the body portion beneath one of said strips and adapted to overlie the strips and fastening means when the boot is 80 secured in position about an inner tube.

In testimony whereof I hereunto affix my signature.

GEORGE G. WILLIAMS.
